US0D1107206S

(12) **United States Design Patent** (10) Patent No.: **US D1,107,206 S**
(45) Date of Patent: ** Dec. 23, 2025

(54) **AIR DIFFUSER**

(71) Applicant: **OBERG ASSOCIATES LTD.**,
Enniskerry (IE)

(72) Inventor: **Mark Van den Bergh**, Enniskerry (IE)

(73) Assignee: **Oberg Associates Ltd.**, Enniskerry (IE)

(**) Term: **15 Years**

(21) Appl. No.: **29/970,117**

(22) Filed: **Oct. 25, 2024**

(30) **Foreign Application Priority Data**

Jul. 1, 2024 (EM) 015065184

(57) **CLAIM**

The ornamental design for an air diffuser, as shown and
described.

DESCRIPTION

FIG. 1 is a front perspective view of an air diffuser showing
my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown throughout the views depict portions
of the air diffuser that form no part of the claimed
design.

1 Claim, 7 Drawing Sheets
